(57) **CLAIM**

The ornamental design for a down jacket as shown and described.

DESCRIPTION

FIG. 1 is a perspective view of a down jacket showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The short dashed broken lines crossing claimed surfaces indicated by surface shading depict claimed stitching. All other broken lines depict portions of the down jacket and form no part of the claim.

1 Claim, 8 Drawing Sheets
